UNITED STATES PATENT OFFICE

2,421,196

SASH LOCK

Fred Granberg, Chicago, Ill.

Application October 12, 1944, Serial No. 558,359

6 Claims. (Cl. 292—336)

1

This invention relates to a self-locking fastener for a check rail window or the like, and relates particularly to such a fastener wherein the bolt is automatically held open while the window is being opened and is automatically moved into locking position when the window is closed.

One object of this invention is to provide a fastener for a check rail window or the like that is automatic in operation and that is held in open position while the window is being opened. Another object is to provide such a fastener wherein the bolt means is moved into locking position when the window is closed. Still another object is to provide such a fastener wherein the two check rails of the window are held in tightly locked position when the window is closed so that it is impossible to open the fastener from the outside by insertion of a thin bar, such as a knife blade, between the two check rails. Still other objects of the invention will become apparent in the detailed description of the invention given hereinafter.

I am able to attain these and other objects of the invention by providing movable bolt means, such as a spring-actuated rotatable plate, on one check rail of a window for engagement with a holding means, such as a catch having an overhanging lip, on the other check rail of the window. I then provide means for automatically holding the movable bolt in locked position when the window is closed, and this can well be the spring of the spring-actuated plate, and means for automatically holding the bolt in open position while the window is being opened. This last means can be a spring-actuated stop which moves into place when the rotatable plate is moved into an unlocked position, and which is knocked out of engagement with the plate once the plate has moved past the lip in the catch. Then, to complete the fastener, there is provided means for automatically locking the window when it is closed. This can be an inclined plane forming the top of the catch and against which the rotatable plate slides until it finally moves into locking position.

A window fastener of the type disclosed herein has many advantages over the old type fastener that is moved entirely by hand. It also has many advantages over the ordinary spring-operated fastener. With this fastener the window is locked by merely closing it, and it is locked so tightly that it cannot be opened from the outside without breaking the glass. The fastener also has the advantage that when the movable portion is shoved by hand to an unlocked position it is automatically held in this position so that the window may be raised with both hands operating on it at the same time.

The invention will be described in detail as applied to the embodiment illustrated in the ac-

2

companying drawings. Of the drawings, Figure 1 is a plan view of the window fastener in a locked position; Figure 2 is a front elevational view similar to Figure 1; Figure 3 is a view taken along the line 3—3 of Figure 1; Figure 4 is a plan view of the fastener in open position; Figure 5 is a front elevational view similar to Figure 4; Figure 6 is an elevation showing the position of the fastener members while the bottom sash of the window is being raised; Figure 7 is an elevation, partially broken away, showing the position of the fastener members when the bottom sash has been raised a still greater distance; and Figure 8 is a view taken along the line 8—8 of Figure 4.

15 In the embodiment shown the fastener comprises a base mounting 10 for the rotatable plate or bolt 11 and fastened to the top of the check rail 12 of the lower sash by means of two screws. Positioned just opposite on the top of the check rail 13 of the upper sash is the mounting 14 for the catch 15 into which the rotatable plate 11 turns to lock the window. The rotatable plate is rotatably mounted on its base by means of a rivet or brad 16, so that it is free to turn through at least a 90° angle when it is in position to engage the overhanging lip 17 in the catch 15. The rotatable plate 11 is provided with a rounded handle 18 for turning the plate and with an inclined surface 19 so that, when it is in locking position, it will wedge against the lip 17 of the catch and hold the two check rails tightly together.

20 In order to move the rotatable plate automatically into locking position there is provided a strong spring 20 of the hair-pin type, preferably located within the base mounting 10 of the rotatable plate 11. This spring is arranged so that it is under great tension when the rotatable plate is in completely open position.

25 The catch 15 which the rotatable plate 11 engages comprises a rounded portion 21 rising to a peak and having an overhanging lip 17 under which the rotatable plate locks when the fastener is in locked position. The rounded portion 21 forms an inclined rounded surface 22 over which the rotatable plate slides when the window is being raised and lowered.

30 In order to hold the rotatable plate 11 in open position when the window is to be raised there is provided a spring-operated stop 23 (Figure 8) mounted in the base 14 of the catch 15. This stop has a retaining surface 24 which automatically engages the rotatable plate 11 and holds it open.

35 40 The operation of the self-locking fastener is as follows: With the fastener in locked position as shown in Figures 1 and 2 the handle 18 of the rotatable plate 11 is grasped by the hand and turned in a counter-clockwise direction. When the plate has reached full open position the

stop 23 is forced up by its spring 25 into engagement with the leading edge of the plate, and thus holds it open. Then the bottom sash of the window can be raised with both hands. As soon as the window sash begins to raise, the rotatable plate 11 slides off the engaging face 24 of the stop 23 and onto the inclined surface 22 of the peaked catch 15. Then the raising of the window is continued to the desired position.

On lowering the window the rotatable plate 11 again engages the inclined surface 22 of the peaked catch and, operating against this inclined surface, is forced around in a counter-clockwise direction, thereby applying tension to the plate's spring 26. When the rotatable plate 11 nears the bottom of the inclined face 22, and has reached the bottom of the overhanging lip 17, the bottom of the plate strikes the top of the retaining surface 24 of the stop 23 which projects out beyond the inclined face 22. Then on lowering the window the last fraction of an inch the stop 23 is pushed down out of the way by the plate and the spring 26 forces the plate around, in a clockwise direction, under the overhanging lip 17; thereby automatically locking the window.

Having described my invention in considerable detail as related to one embodiment of the same it is my intention that the invention be not limited to these details but rather be construed broadly within its spirit and scope as set out in the accompanying claims.

I claim:

1. A self-locking fastener for a check rail window or the like comprising: a rotatable locking plate mounted on the check rail of one sash of said window; a catch mounted on the check rail of the other sash of said window for engagement with said rotatable plate to lock the window; means including an inclined surface integral with the catch for automatically moving the rotatable plate into unlocking position as the window approaches closed position; spring means for moving the rotatable plate into locking position when the window reaches closed position; and means including a spring-actuated stop for holding the rotatable plate in open position for opening the window, said stop having an engaging face adjacent to but projecting beyond said inclined surface so that the rotatable plate pushes said stop aside when the window is being closed.

2. A self locking fastener for a check rail window or the like comprising; a rotatable bolt means mounted on the check rail of one sash of the window; catch means mounted on the check rail of the other sash and adapted to be engaged by said bolt means to lock the window; cooperating cam surfaces on the catch means and bolt means for automatically moving the bolt means out of locking position upon closing of the window; spring means for moving the bolt into locked position; and means on the catch means check rail adapted to engage the bolt upon manual turning thereof to retain the bolt in unlocked position, said means being so positioned that the rotatable bolt is moved out of operative engagement therewith by movement of the window toward open position.

3. A self locking fastener for a check rail window or the like comprising; a rotatable bolt means mounted on the check rail of one sash of the window; catch means mounted on the check rail of the other sash and adapted to be engaged by said bolt means to lock the window; coop-

erating cam surfaces on the catch means and bolt means for automatically moving the bolt means out of locking position upon closing of the window; spring means for moving the bolt to its locking position; and means adjacent the catch means adapted to engage the bolt upon manual turning thereof to retain the bolt in unlocked position, said means being released from such engagement upon opening of the window.

4. A self locking fastener for a check rail window or the like comprising; a rotatable bolt means mounted on the check rail of one sash of the window; catch means mounted on the check rail of the other sash and adapted to be engaged by said bolt means to lock the window; cooperating cam surfaces on the catch means and bolt means for automatically moving the bolt means out of locking position upon closing of the window; spring means for moving the bolt to its locking position; and means adjacent the catch means adapted to engage the bolt upon manual turning thereof to retain the bolt in unlocked position, said means being released from such engagement upon opening of the window, and projecting into the path of the bolt when the window is closed so as to be pushed downwardly out of operative engagement with the bolt until the bolt is manually turned for raising the window.

5. An attachment for automatically locking a window provided with a lock of the conventional type wherein there is a rotatable bolt on one check rail comprising a plate having an upstanding cam flange and cooperating catch means on the other check rail, including an over-hanging lip, comprising: automatic means for moving the bolt to locking position under said lip; and a member adapted to automatically engage the leading end of the cam flange after said bolt has been manually turned to unlocked position to maintain the bolt in unlocked position.

6. An attachment for automatically locking a window provided with a lock of the conventional type wherein there is a rotatable bolt on one check rail comprising a plate having an upstanding cam flange and cooperating catch means on the other check rail, including an over-hanging lip, comprising: automatic means for moving the bolt to locking position under said lip; and a member adapted to automatically engage the leading end of the cam flange after said bolt has been manually turned to unlocked position to maintain the bolt in unlocked position, said member being pivotally mounted on the catch means check rail so that relative movement of the check rails releases the engagement of the member and bolt, permitting the automatic means to move the bolt to locking position.
